(57) **CLAIM**

The ornamental design for plug with a pull ring, as shown and described.

DESCRIPTION

FIG. 1 is a perspective view of a plug with a pull ring. FIG. 2 is a front view of the plug with a pull ring of FIG. 1. FIG. 3 is a back view of the plug with a pull ring of FIG. 1. FIG. 4 is a top view of the plug with a pull ring of FIG. 1. FIG. 5 is a bottom view of the plug with a pull ring of FIG. 1. FIG. 6 is a left side view of the plug with a pull ring of FIG. 1; and, FIG. 7 is a right side view of the plug with a pull ring of FIG. 1.

In the figures, trademarks are shown in dashed lines and do not form part of the claimed design. Also, portions of the plug with a pull ring shown in broken lines form no part of the claimed design.
